CLAIM

I claim the ornamental design for a closure, as shown and described.

DESCRIPTION

FIG. 1 is front top perspective view of an embodiment of the claimed design;

FIG. 2 is rear top perspective view of FIG. 1;

FIG. 3 is rear bottom perspective view of FIG. 1;

FIG. 4 is front bottom perspective view of FIG. 1;

FIG. 5 is a top view of FIG. 1;

FIG. 6 is a bottom view of FIG. 1;

FIG. 7 is a front view of FIG. 1;

FIG. 8 is a rear view of FIG. 1;

FIG. 9 is a right side view of FIG. 1; and,

FIG. 10 is a left side view of FIG. 1.
